DESIGN FOR A WEIGHING SCALE

Henry Dreyfuss, New York, N. Y., assignor to
Fairbanks, Morse & Co., Chicago, Ill., a corpo-
ration of Illinois

Application June 22, 1944, Serial No. 114,151

Term of patent 14 years

(Cl. D52—10)

To all whom it may concern:

Be it known that I, Henry Dreyfuss, a citizen of the United States, residing at New York city, in the county of New York and State of New York, have invented a new, original, and ornamental Design for a Weighing Scale, of which the following is a specification, reference being had to the accompanying drawing, forming part thereof. In a drawing, the figure is a perspective view

of a weighing scale, showing my new design, the opposite side of the scale presents substantially the same appearance as the side shown and the back of the scale is plain.

I claim:

The ornamental design for a weighing scale, as shown and described.

HENRY DREYFUSS.
